UNITED STATES PATENT OFFICE.

WILLIAM GAUSE, OF FORT WAYNE, INDIANA.

REAPING-MACHINE.

SPECIFICATION forming part of Letters Patent No. 274,931, dated April 3, 1883.

Application filed December 11, 1882. (No model.)

To all whom it may concern:

Be it known that I, WILLIAM GAUSE, of Fort Wayne, county of Allen, and State of Indiana, have invented a new and useful Improvement 5 in Reaping-Machines, of which the following is a full, clear, and exact description, reference being had to the accompanying drawings, making part of this specification.

My improvement relates to a novel construction and arrangement of the reeling, raking, and gaveling mechanisms, whereby the grain is drawn in to the cutters, carried inward and delivered to the gavel-forming and gavel-discharging devices in a standing position; to the 10 means for discharging the gavels or bundles, and to certain details of construction and arrangement of parts of the machine, as herein-after explained.

In the accompanying drawings, Figure 1 represents a front elevation of a reaping-machine with my improvement applied. Fig. 2 is a plan or top view of the same. Fig. 3 is a bottom view of a portion of the same, and Fig. 4 is a rear elevation of the gaveling-platform and its 25 attachments.

A represents the main frame of the machine, consisting of a bar or plate of metal set upon edge, and with its ends bent at right angles to the body portion, which is arranged on the 30 stubble side of the wheel B in a longitudinal plane parallel with the outer face of said wheel, the bent ends *a* and *a'* crossing the path of the wheel, in front and rear thereof, as shown. The wheel B is made fast on its axle, and the latter 35 rotates in a sleeve-bearing, *b*, formed upon or secured to the longitudinal portion of the frame-bar, at or near the center of its length. The wheel B is provided on its inner face with a bevel-gear, *B'*, with which a bevel-pinion, *B''*, engages, said pinion being secured 40 to a longitudinal shaft, C, having bearings in the bent ends *a* and *a'* of the frame-bar A, and provided on its forward end with a crank wrist or disk, from which motion is imparted to the 45 sickle-bar. The forward transverse arm, *a*, of the frame extends beyond the bearings for the shaft C, and is bent or twisted at *a''* from a vertical position, or one on edge, to a horizontal 50 position, its extended horizontal end *a'''* forming a support for or point of attachment to the frame of the finger-bar D. To the inner end of the finger-bar is secured a small

rectangular platform, E, arranged in rear of said bar, and serving as the gaveling-platform, and as a support for the gaveling and gavel-discharging mechanism, the outer or grain side of said platform being secured to a short arm or bar, E', rigidly secured at its forward end to the finger-bar. This arm or bar E' may, if preferred, form a heel-extension of the outer 55 shoe, and serves, in connection with a heel-extension of the outer shoe or divider, F, and finger-bar D, to form a support for the raking and reeling apparatus, which will now be described.

G and G' represent two uprights arranged perpendicularly to the upper face of the finger-bar, and rigidly secured at their lower ends to said bar near its rear edge. To the upper end of these uprights G and G' is rigidly secured 60 a transverse bar, H, arranged in a horizontal plane above and parallel with the finger-bar, with its ends projecting beyond the supports G and G'.

I is an upright shaft mounted in bearings, one 65 at its lower end in the arm E and another at its upper end in the inner end of the bar H, and provided near said bearings with sprocket-wheels I' and I''. The heel end of the outer shoe or divider, F, is provided with a short 70 upright stub-axle on which a sprocket-wheel is mounted loosely, and the outer end of bar H is provided with a short pendent axle, f, arranged in line with said upright axle on the divider, and upon which is similarly mounted 75 a sprocket-wheel, I''. Endless chains J and J' connect the sprocket-wheels on the shaft I with the sprocket-wheels on the short shafts above named. The shaft I extends below its lower bearing in the bar E', and is provided 80 with a bevel-gear, B', meshing with a similar bevel-gear, B'', on a longitudinal shaft, C', mounted in bearings in pendent lugs on the arm E'. This shaft is provided with a sprocket-wheel, C'', near the center of its length, and motion is imparted to the shaft C', and thence 85 to shaft I, through an endless chain connecting the sprocket-wheel C'' with a similar wheel, C'', on the shaft C. The chains J and J' are provided on their outer faces with short vertical sleeves, forming bearings for upright rake heads or shafts j, of which there may be any desired number, the sleeve-bearings of the upper sprocket-chain being arranged directly 90

over those of the lower one, the shafts j connecting the chains, as shown. The shafts j are provided each with a series of teeth, j' , projecting obliquely forward and inward, (when 5 on the forward portion of the chains and moving inward toward the machine-frame,) and by preference made, each lower tooth a little longer than the one immediately above it, and also bent or curved to form a more acute angle 10 with the carrying-chain, so as to have its point or end in advance of or projected beyond the tooth or teeth above it, as by this arrangement the butts of the grain are first seized by the lower fingers or teeth and are drawn in to the cutters, and this action serves at the same time to draw the upper ends of the straw inward and to lay them in the shorter upper fingers. The upper ends of the rake-heads j are extended beyond the chain J , and 15 are bent at a right angle, forming on each head or shaft a horizontal crank-arm, j^2 , and the extreme end of this arm is bent downward at a right angle to the arm j^2 , and is provided with a friction-roller, j^3 , for a purpose which 20 will be explained.

The bar H is provided on its forward edge with an upright lip or flange, H' , against which the rollers j^3 rest when the rakes are moving inward, and which serves to hold the rake-teeth in the position above described during 25 such inward operative movement. This lip is bent or deflected rearwardly over the sprocket-wheel I , at its inner end, h , for permitting the rake-heads to move around said wheel, and at the same time to hold the teeth j' up to their 30 work, and a similar deflection, h' , at the outer end serves to assist in forcing the roller outward in advance of the rake-head in passing said end. A bar, H^2 , is located immediately 35 in front of the flange H' , supported by the forward pendent arms of angular or U -shaped (inverted) brackets h^2 h^3 , the rear arms of which are secured to the rear face of the flange or lip H' . The bar H^2 is sufficiently removed 40 from the flange H' to permit the free passage of the rollers between them, and serves not only to hold the stalks of grain free from the driving-chain, but also to prevent the weight of the grain from drawing the upper end of 45 the rake-heads forward out of proper working position. Similar strips, H^3 H^4 , arranged below the bar H^2 , are secured at their outer ends to a standard, F' , on the outer shoe or divider, and extending thence in front of the path of 50 the rake-heads, are curved at the inner end of such path to conform thereto, to a point where the rake-heads begin their outward or return movement, where they are deflected rearward from said path and are secured to a standard, 55 F^2 , secured to the outer edge of the platform E , near its rear outer corner. By this arrangement of the strips or bars H^3 H^4 they serve, in connection with the bar H^2 , to uphold the grain in a standing position against the action of the rake-teeth, to clear or strip the latter as 60 they start upon their outward or return movement, and to assist in forming the grain into

gavels, and in holding the grain in an upright position until the gavel is completed and ready to be discharged or bound.

The finger-bar D has a strip or plate, D' , secured to its rear edge, which serves to protect the lower sprocket chain from the stubble and other obstructions, and also at its outer end as a support for an angle-iron, D^2 , the upright portion or lip e of which serves, as the 70 rake-heads approach the end of their outward or return movement, to rock the teeth backward, and, in connection with the deflection of the lip or flange H' , to rock the crank-arms j^2 75 into proper position for holding the rake-teeth up to their work on their inward movement, as explained.

To the inner end of the finger-bar, or to the end of the arm a^3 , to which said bar is connected, is secured an upright, L , provided with a series of curved fingers, l l , arranged one over another and rigidly secured at one end to said standard. These fingers project forward from the standard and are curved outward and 80 rearward, giving them each the form of an irregular U or loop, the arms l l of which are elongated and extend obliquely across the platform, terminating near the rear ends of the strips H^3 H^4 , and forming yielding arms, between which and the strips H^3 H^4 the grain is left standing in an upright position, the grain as it is brought in by the rake-teeth being gradually crowded back on a platform between said strips and yielding fingers. The upright L is 85 by preference provided with a pivot extending through its supporting-bar, and provided with a screw-thread and nut on its lower end for permitting the adjustment of the upright on such pivot, and thereby adjusting the angle 90 of relation of the fingers to the strips H^3 H^4 , as may be required to adapt them to the condition of the grain being operated upon, but any suitable means may be employed for effecting such adjustment.

The platform E is provided near its rear inner corner with bearings for an upright shaft, M , the upper end of which is squared to adapt it to receive and actuate a grain-receiving and gavel-discharging device, N . This device consists of a quadrant, or, rather, of a hub, N' , having a perforation conforming to the shape of the shaft M in horizontal section, and fitting said shaft, and provided with three arms, n n' n^2 , the two first-named being connected at their outer end by a section of a rim curved in the arc of a circle of which the shaft M is the center, giving said part of the device a skeleton-quadrant form, with the radial arm n^2 distinct therefrom, and connected with said quadrant only through a common hub or center. This arm crosses the space between the fingers l and the bars H^3 H^4 near their rear ends, and serves to receive and uphold the grain brought in by the rakes. The arm n' is made in form 110 resembling the letter S , the curved portion at its outer swinging end being adapted to partially encircle the gavel and to compress the same; and it may also serve as the needle-arm 115

for carrying the end of the binding material around said gavel, where the grain is to be bound before being discharged. The quadrant or partial rim n^2 , connecting the arms n and n' , serves to prevent the incoming grain from getting behind the arm n' and interfering with its being retracted after it has been operated to discharge the gavel or bundle.

The shaft M is provided with a number of holes, and the gavel-discharging device may be held at any desired height to adapt it to the grain being operated upon by means of a pin passed through one of said holes under the hub N' . The shaft projects slightly below the platform E , and is provided on its lower end with a crank-wheel, P , from which a connecting-rod, p , extends to a crank-wheel, P' , mounted loosely on the rear end of a shaft, C' . The hub of the crank wheel or disk P' is provided on its forward end with a clutch-face, adapting it to engage with a corresponding clutch-face on a collar, c^5 , fast on the shaft C' . The said hub of wheel P' is grooved to receive the bent ends of a U-shaped loop, q , attached to the outer end of the lever r , pivoted at r' to the lower face of the platform. The inner end of the lever r extends past the crank wheel or disk P , and is connected by a spring, s , with the platform, as shown, the tension of said spring being exerted to hold the crank-wheel P' out of engagement with the clutch-collar c^5 , and loose on the shaft. Midway between the pivot r' and the spring s the lever r is provided on its upper face with a friction-roller, r^2 , which rests against the disk P ; and the latter has a notch or recess formed in its periphery at P' , in which the roller r^2 rests when the gaveling-arm n^2 is in position to receive the incoming grain. As the grain becomes compressed against said arm n^2 in quantity sufficient to form a bundle of the desired size, the further accumulation of the grain crowds said arm back, partially rotating the disk P and displacing the roller r^2 from the notch p ; and said disk, crowding the roller back, together with the arm of lever r , to which it is attached, serves to throw the crank-wheel into engagement with the clutch-collar c^5 ; and said crank-wheel, acting through the pitman p on the crank-wheel P and shaft M , rocks the gavel-discharger backward, causing the gavel to be thrown over the rear edge of the platform, discharging it either upon the ground or into any suitable receptacle. The crank or crank-wheel P' is of shorter radius than crank-wheel P , and serves merely to vibrate the latter just enough to cause the ejector n' to discharge the gavel or bundle, the roller r^2 , as the wheel P completes its return movement, being drawn into the notch p' , thereby throwing the crank-wheel out of action until the grain again presses the arm n^2 back, as described.

At that part of the platform where the gavel or the bound bundle, as the case may be, is discharged, is a low gate, t , hinged by its lower edge to the rear edge of the platform, and in an upright position by a spring, t' . (See

Fig. 2.) This gate serves to prevent the butts of the grain from slipping or being crowded off the platform until the gavel is completed, 70 and then yields to permit the discharge of the gavel or bundle, or, where the grain is tall and the ejecting device well elevated to accommodate such tall grain, the gate serves to trip the butt-end of the bundle or gavel, causing the 75 latter to be thrown over on its side.

For relieving the machine of side draft or the dragging of its outer end, I prefer to locate the grain-wheel behind the cutting apparatus and the upright raking and reeling device described at about the center of their length. The grain-wheel U is mounted on a short shaft attached to the rear end of an arm, V , about in the same transverse vertical plane with the axis of the main driving-wheel B , the forward 85 end of said arm V being connected rigidly with the finger-bar at or near the center of its length, as shown.

The tongue W of the machine is hinged at its rear end to the inner end of the forward 90 arm, $a a^3$, of the angular frame-bar, and is provided with a hound or brace, w , extending obliquely to the outer front corner of said angular frame-bar, and pivoted in a lug, X , and said brace, extending through said lug, is bent 95 forward and forms a crank-arm, w' , to which one end of a lever, y , pivoted in any suitable support on the frame-bar, is attached. The lever may be held at any desired adjustment by a toothed rack or other suitable device, and 100 serves by its adjustment to rock the machine on its wheels B and V in a manner well understood.

Having now described my invention, what I claim as new is—

1. In a reaping-machine, upright shafts at each end of the cutting apparatus, provided with sprocket-wheels, in combination with endless chains carrying upright rake shafts or heads, and mechanism for moving said rake-heads inward across the path of the cutters for delivering the cut grain in an upright position upon a gaveling-platform at the inner end of the cutting apparatus, substantially as described.

2. In a reaping-machine, the upright reeling and raking mechanism consisting of the endless chains arranged one over another, and carrying upright rake heads or shafts provided with the teeth or fingers set obliquely, as described, whereby the points are made to enter the standing grain and gather it in to the cutters.

3. The upright rake-heads provided with crank-arms, in combination with the guiding ledge or track for holding said rake-heads in working position, and mechanism for moving said rake-heads transversely across the path of the cutters, substantially as and for the purpose described.

4. The upright rake-heads provided with the obliquely-arranged teeth, in combination with the actuating-chains and the supporting-strips arranged in front of the path of said heads, and

operating, in connection with the rake-fingers, to support the grain in a standing position, substantially as described.

5. The upright rake-heads attached to and carried by endless chains, in combination with the supporting and clearing or stripping bars H^3 and H^4 , the yielding fingers l , and the supporting-arm n^2 of the yielding device N , substantially as described.

10. The gaveling-platform located at the inner end of the cutting apparatus, in combination with mechanism for delivering the grain thereto in an upright or standing position, and means for upholding and compressing the grain thereon, substantially as described.

15. The gavel upholding and ejecting device N , mounted upon an upright shaft, in combination with mechanism adapted to be thrown into action by the pressure of the grain on the gavel-upholding device for effecting the discharge of the gavel or bundle, substantially as described.

20. The combination, with the gaveling-platform E and means for upholding and compressing the grain thereon, of the pivoted gate crossing the path of discharge of the grain, substantially as described.

25. The upright shaft M , in combination with the grain holding and ejecting device N , made adjustable vertically on said shaft, substantially as and for the purpose described.

10. The upright L , located at or near the heel end of the finger-bar, and provided with curved and yielding fingers l , substantially as described, in combination with the bars H^3 35 and H^4 , mechanism for delivering the grain in a standing position to said fingers, and mechanism for discharging the grain, substantially as described.

11. The upright shaft M , carrying the bundle holding and ejecting device, in combination with the crank-wheels P and P' , arranged and operating substantially as described.

12. The angular frame-bar A , provided with bearings for the main drive-wheel axle and 45 crank-shaft, and having its forward transverse arm turned or twisted from a vertical position, or one on edge, to a horizontal position, in combination with the finger-bar, secured to said arm, substantially as described.

13. The hinged pole or tongue, in combination with the obliquely-arranged tongue-brace w , pivoted to the frame, and provided with a crank arm or lever, w' , and a lever, y , connected therewith for rocking the frame on its supporting-wheels, substantially as described.

In testimony whereof I have hereunto set my hand this 8th day of December, A. D. 1882.

WILLIAM GAUSE.
